UNITED STATES PATENT OFFICE.

ROBERT JOSEPH DILLON, OF KILLALOE, ONTARIO, CANADA.

CATTLE-GUARD.

1,014,696.

Specification of Letters Patent. Patented Jan. 16, 1912.

Application filed February 15, 1911. Serial No. 608,813.

To all whom it may concern:

Be it known that I, ROBERT JOSEPH DILLON, of the town of Killaloe, in the Province of Ontario, Dominion of Canada, have 5 invented certain new and useful Improvements in Cattle-Guards, of which the following is a specification.

My invention relates to improvements in "railroad cattle guards", and the objects 10 of my invention are to devise a simple, cheap and easily constructed cattle guard, which may be laid between the rails of a railway, or in any other place, where it is necessary or desirable to prevent the passage of cattle.

In general, my invention consists of a frame, in which are secured a number of inclined or beveled slats and also a plurality of eccentrically mounted rollers, located 20 above said slats and having their bearings in the frame, the various parts of the device being constructed and arranged in detail as hereinafter more particularly described.

Figure 1 is a plan view of my device in 25 use. Fig. 2 is a sectional view on the line 2—2. Fig. 3 is an enlarged perspective view of one of the rollers.

In the drawings, like letters of reference indicate corresponding parts.

30 In the drawings, A represents my cattle guard and consists of two parallel side pieces 10, between which are secured a number of inclined or beveled slats B provided with inclined surfaces 11. Located above 35 said slats B, are a plurality of eccentrically mounted rollers C, provided with eccentric pintles 12, which have their bearings in the side pieces 10. If desired, instead of mounting the rollers eccentrically they might 40 be loaded on one side. The rollers C are so situated with regard to the slats B, that any object placed on the rollers C would be immediately precipitated upon the inclined surfaces 11 of the slats B, whence the animal's 45 foot, will slide below the slat and may only be withdrawn in a rearward direction.

The cattle guard is designed to rest between the rails 13 of a railway track, and

may be secured to the sleepers 14 by any suitable means but it is to be understood that 50 similar guards might easily be placed on each side of the track to prevent even the approach of the animal.

As many changes could be made in the above construction and many apparently 55 widely different embodiments of the invention within the scope of the claims could be made without departing from the spirit or scope thereof, it is intended that all matter contained in the accompanying specifications 60 and drawings shall be interpreted as illustrative and not in a limiting sense.

What I claim as my invention is:

1. A cattle guard comprising a frame, inclined slats located therein and smooth rollers located above said slats and extending parallel to the same.

2. A cattle guard, comprising a frame adapted to rest between the rails, slats located therein provided with inclined surfaces and smooth rollers located above and parallel with said slats adapted to precipitate the feet of the cattle upon the inclined surfaces of said slats.

3. A cattle guard, comprising a frame, 75 slats located therein, provided with inclined surfaces and eccentrically mounted smooth rollers extending parallel with the slats and from end to end of the same adapted to precipitate the feet of the cattle upon the inclined surfaces of said slats.

4. A cattle guard comprising a frame, parallel slats extending across the same and being spaced a distance apart and formed with inclined surfaces, a series of rollers extending parallel to the slats located above the uppermost edges of the slats and adapted to precipitate the feet of an animal onto the slats.

In witness whereof I have hereunto set 90 my hand in the presence of two witnesses.

ROBERT JOSEPH DILLON.
